SEAMLESS STOCKING AND METHOD OF MAKING THE SAME

Application filed October 23, 1930. Serial No. 490,756.

My invention relates to tubularly knitted stockings or like articles, and more specifically to a stocking having an improved heel construction, and to the method of making the same.

10 A main object is to provide a heel pocket of relatively enlarged size adapted to insure a more natural conformation of the foot and leg portions with greater wearing comfort and neater fit over the instep.

Another object is to provide an elastic stretch in the heel pocket to facilitate free introduction of the foot and a smooth close fit when in use.

15 Another object is to provide for tapered heel extensions into the sole and rear leg portions to increase wear resistance at these points and improve the appearance of the stocking.

20 Another object is to avoid naturally weak heel spots by the arrangement and formation of the suture junctions.

With these main objects outlined, and with others that will later hereinafter appear, my invention comprises the novel stocking heel structure and the method of making the same as will now be fully described in detail in connection with the accompanying drawing, the novel features of which are specifically set forth in the appended claims.

Referring to the drawing,—

Fig. 1 is a conventional diagrammatic side view of a stocking foot and portion of the leg and indicates a heel pocket embodying my invention.

40 Fig. 2 is a similar showing of a stocking in which the heel pocket embodies a modification of the preferred construction indicated in Fig. 1.

Fig. 3 shows diagrammatically the knitting and nonknitting divisional arrangement of the circle of needles of a usual circular knitting machine at various successive 45 steps in the production of a stocking embodying my invention.

It is commonly recognized in the art that the ordinary heel pocket of a tubular stocking formed by a single narrowing and widening 50 operation on a rear portion of the circle of

needles during reciprocative knitting, produces a heel pocket of less than desired size to angularly project the foot portion relative to the leg so as to conform to the natural bend of the human foot, with the consequence 55 that for a given foot length there is an excess of length over the instep causing unsightly wrinkling when in use.

My improved heel pocket not only overcomes the above recognized defects and produces a stocking of natural foot conformation, but has also other desirable features both of construction and appearance as will be set forth in the following description.

It will be understood that my invention applies alike to full length or half hose, the preferred embodiment of Fig. 1 showing the leg portion 5 broken away above the heel pocket. This leg portion 5 may be produced as heretofore by circular or round and round 70 knitting on a full circle of needles to form a seamless tube, such tubular knitting continuing to the course line a—b—c—d, which in the drawing appears as angular, but the loops of which engage the full circle of 75 needles at the end of the leg formation, as is clearly indicated in "position 1" of Fig. 3.

In Fig. 1 the line a—b—c—d appears on one side of the stocking only, but it will be understood to be a tubular fabric flattened 80 on front and rear vertical medial lines, with an identical opposite side, and reference to one side is to be taken as referring to both unless otherwise specified.

At the aforesaid end course a—b—c—d of 85 the leg portion 5, the heel pocket formation begins by added part circular courses in the rear portion only, produced as usual by reciprocative knitting on part of the circle of needles, designated for convenience as heel needles, while the remaining needles may be designated as instep needles.

The usual heel pocket, as well understood, is made on the heel needles by a single narrowing and widening process, with midway diagonal sutures on each side, such pocket as aforesaid being of less than desired size to properly extend the foot at a conforming normal angle. And during such heel forma- 100

tion, as known, the instep needles with retained loops are shifted out of knitting action.

To produce the enlarged heel pocket 6 of my present invention, I preferably form the heel pocket of a plurality of widened and narrowed sections, the preferred showing of Fig. 1 indicating three with three suture seams on each stocking side, the outer ones defining the marginal edges of the pocket.

10 The first section comprises the area on each side within the lines $b-c$, $c-d$, $d-g$ and $g-f-e-b$, the lines $b-c$ representing suture junctions with the loops of the end course of the leg portion.

13 The adjoining section comprises the area within the lines $g-f-e$, $e-h$, and $h-g$, with the lines $f-e$, representing suture junctions on each side with the first section.

20 The third section comprises the area within the lines $h-e$, $e-i-j$, and $j-h$, with line $e-i$ representing suture junctions on each side with the foot portion 7; and line $j-i-e-b-a$ representing the first full circular course of the foot extension.

23 These several heel pocket sections forming my preferred enlarged heel pocket, may be better understood by a description at this point of a means of knitting the same on a usual knitting machine.

26 Referring to Fig. 3, "position 1" has been referred to as showing the full circle of needles at the end course of loops of the leg portion 5.

28 "Position 2" indicates the needles as divided preparatory to producing my improved heel, first section; all the instep needles being temporarily shifted out of knitting action, and also certain of the heel needles, leaving only certain intermediate rear ones which embrace the wale loops on both stocking sides between the letters d and c Fig. 1. The loops of the temporarily shifted needles are retained thereon for subsequent knitting as heretofore

45 and well understood, and it will be further understood without further statement, that each time needles are temporarily shifted, they retain their loops. With the needles thus divided, reciprocal knitting on needles d to c begins, with single needle additions in successive courses, to widen in well

50 known manner, until all the needles between the letters c to b have been restored to knitting action, such singly added needles forming the sutures $c-b$. At this point all the heel needles have been restored to knitting action, "position 3" indicating the needles at the completion of the first heel section.

48 Before starting the second heel pocket the same heel needles that were temporarily shifted out of knitting action at the beginning of knitting the first section, are again temporarily shifted out of action leaving only the needles embracing the wale loops on both stocking sides between the letters g and f ,

which it will be seen are the same wales between the letters d and c ; "position 4," Fig. 3 indicating this division, and is identical with "position 2." Now by reciprocal knitting and singly added needles, until all the needles between the letters f to e have been restored, the second section is formed, the line $f-e$ indicating suture junctions with the first section, and the needles between the letters e and b remaining out of knitting action, the 75 needle division at this point being indicated in "position 5" of Fig. 3.

The third section is produced, starting with the needle division of "position 5" by reciprocal knitting and singly shifting out of 80 knitting action the needles between the wales e and i , when knitting is suspended with a needle division indicated in "position 6"; it being noted that I prefer to shift out of action less than the number of needles singly restored in the second section, leaving a greater 85 number of wales between the letter i and j , than there are between the letters f and g .

The heel pocket is now completed, and at 90 this point I return bodily all the shifted needles completing the full circle as indicated in "position 7" and resume circular or round and round knitting to produce the foot portion 7 and by subsequent usual reciprocal knitting the ordinary or any toe pocket 8; the latter being seamed in known manner to complete the stocking. The line $e-i$ represents 95 junction sutures with the first foot course.

My improved heel pocket, made as above 100 set forth, provides a heel pocket of enlarged size, which angularly projects the foot portion 7 so as to naturally conform to the bend of the human foot. This enlarged heel pocket adds also to the length of the sole portion of 105 the stocking foot, permitting a minimum of top length in the latter for a given size, and insures an unwrinkling fit at the instep. Furthermore the rear wales extending from $d-c$ to $i-j$, and additional ones from part of $f-e$ to $i-j$ are continuous extensions from the leg 110 through the heel pocket and into the foot portion giving free elasticity to assume the proper heel shape. Also it will be seen that the wales between e and b extend from suture lines $e-b$ directly into the foot portion, providing elasticity both lengthwise and laterally to permit ready stretching when the foot is inserted and subsequent return to insure a neat fit; the wales being thus free due to the end b of suture $c-b$ ending in the lines $h-a$ at approximately medial points on each side while the point e at the junction of sutures $f-e$ and $e-i$ is spaced from b , due to the 115 second and third heel sections being formed on less than the full number of heel needles. And furthermore the sutures $c-b$ and $c-i$ extend diagonally across the wales of the heels, so as to form tapered heel extensions into the leg portion 5 and foot portions 6, increasing the size of the heel and forming 120

125

slightly tapered heel projections, which may be used alone as a pointed heel reinforcement, or in conjunction with a heel reinforcement commonly added during the knitting of the leg portion 5. In the first section, projecting into the rear of the leg, I preferably employ a different thread or yarn matching or harmonizing with the leg thread, such different thread being used through the portion enclosed by lines $b-c$, $c-d$, $d-g$ and $g-f$ — $e-b$, with a change of thread in the remaining heel portion. The sutures $c-b$ and $f-e-i$ on each side of the stocking form ornamental lines, differing from the usual suture junctions in that in each one the needles are bodily shifted in one direction as distinguished from single shift and single return ordinarily employed. Such suture formation, as will be readily understood, produces a closer loop juncture, neater in appearance and of increased strength. And the suture lines $c-b$ and $e-i$ form neat marginal edges for the heel pocket.

The particular needle division of Fig. 3 is preferred, but may be modified within the spirit of my invention. And in Fig. 2 I have indicated a somewhat different heel pocket having three sections and in which the section marginal and intermediate suture lines converge at apex points m on each side of the heel pocket, produced in a manner similar to that above described except that all the heel needles are employed in forming sutures $m-n$ which corresponds to $b-e$ and $m-o$ which corresponds to $e-f$; suture $m-p$ is shown as shorter in the preferred structure.

From the foregoing description it is believed the nature of my improved heel pocket and the method of making the same will be readily understood, and its essential advantages have been clearly pointed out. And it is to be understood that other modifications than the one disclosed, may be readily developed, all within the spirit of my invention as defined in the following claims.

What I claim is:

1. A seamless stocking having an enlarged heel pocket formed of angular sections and characterized by having on each side thereof three suture seams, the intermediate one defining a mid-heel junction of section loops, and the other two defining respectively marginal heel section loop junctions with the leg and foot portions, the inner end of one of said marginal sutures being spaced away for a plurality of wales from the inner ends of the other sutures to provide extensible areas at the inner ends of the heel pocket on each side of the stocking.

2. The method of knitting a seamless stocking having an enlarged heel pocket, which comprises forming by circular knitting a tubular leg portion extending to the instep and heel, then by reciprocative part-circular gradually widening knitting form-

ing a heel section with marginal leg-connecting sutures extending on each stocking side diagonally across the wales to medial points adjacent the instep portion, then by further reciprocative part circular knitting first gradually widening and then gradually narrowing to form added integral heel sections with suture junction lines on each side of the stocking defining marginal junctions with the aforesaid leg-connected section, then resuming full circular knitting to form a tubular foot portion joined to said heel pocket by marginal suture seams on each side of the stocking extending diagonally across the wales to form a tapered heel projection into the bottom of said foot portion, and finally knitting and finishing a toe pocket at the end of the tubular foot portion.

3. The method of knitting a seamless stocking having an enlarged heel pocket, which comprises forming by circular knitting a tubular leg portion extending to the instep and heel, then by reciprocative part-circular gradually widening knitting forming a heel section with marginal leg-connecting sutures extending on each stocking side diagonally across the wales to medial points adjacent the instep portion, then by further reciprocative part circular knitting first gradually widening and then gradually narrowing to form added integral heel sections of less width than the leg-connected section and with marginal suture junction lines with the latter on each side of the stocking, then resuming full circular knitting to form a tubular foot portion joined to said heel pocket by marginal suture seams on each side of the stocking extending diagonally across the wales to form a tapered heel projection into the bottom of said foot portion, and finally knitting and finishing a toe pocket at the end of the tubular foot portion.

4. The method of knitting a seamless stocking having an enlarged heel pocket, which comprises forming by circular knitting a tubular leg portion extending to the instep and heel, then by reciprocative part-circular gradually widening knitting forming a heel section with marginal leg-connecting sutures extending on each stocking side diagonally across the wales to medial points adjacent the instep portion, then by further reciprocative part circular knitting first gradually widening and then gradually narrowing to form added integral heel sections with suture junction lines on each side of the stocking defining marginal junctions with the aforesaid leg-connected section, then resuming full circular knitting to form a tubular foot portion joined to said heel pocket by marginal suture seams on each side of the stocking extending diagonally across the wales to form a tapered heel projection into the bottom of said foot portion, and the sutures on each side of the stocking converging to apex points adjacent

the instep, and finally knitting and finishing a toe pocket at the end of the tubular foot portion.

5. The method of knitting a heel pocket
5 which comprises bodily throwing all the in-
step needles and the greater portion of the
heel needles out of action and then widening
to knit a heel section by reciprocative kni-
ting until all the heel needles have been
10 gradually restored to action, again bodily
throwing said greater portion of the heel
needles out of action and widening until less
than said portion of heel needles have been
15 gradually restored to action, and then nar-
rowing upon said lesser number of heel
needles until only a portion of the heel needles
remain in action.

6. A seamless stocking having a heel
pocket comprising contiguous widened sec-
20 tions with unsutured laterally and longitudi-
nally stretchable wales between the inner
ends of said widened sections.

7. A seamless stocking having an enlarged
heel pocket comprising; a widened section
25 having marginal suture loop junctions with
the leg portion of the stocking; a second
widened section contiguous to said first sec-
tion and having marginal suture loop junc-
30 tions with portions of said first section; and
an adjacent narrowed section having mar-
ginal suture loop junctions with the foot
portion of the stocking, said second widened and
said narrowed sections being relatively
35 smaller than said first widened section so
that their inner ends are spaced away for a
plurality of wales from the inner ends of
said first widened section to provide unsu-
tured, extensible areas at the inner ends of
40 said heel pocket on each side of the stocking.

8. A tubularly knitted stocking having
widened and narrowed heel pocket sections
with suture apex points on each side of the
stocking, and a contiguous widened heel ex-
45 tension into the leg of the stocking formed
with leg sutures on each side of the stock-
ing having their inner ends terminating
above said apices and providing intermedi-
ate unsutured areas which are extensible lat-
erally and longitudinally.

- 50 In testimony whereof I affix my signature.
HARRY E. KATZENMOYER.
